UNITED STATES PATENT OFFICE.

SAMUEL E. WINDER, OF CHICAGO, ILLINOIS.

DESIGN FOR A CROUSTADE.

Application filed February 23, 1924. Serial No. 8,708. Term of patent 14 years.

To all whom it may concern:

Be it known that I, SAMUEL E. WINDER, a citizen of the United States, residing at Chicago, in the county of Cook and State of Illinois, have invented a new, original, and ornamental Design for Croustades, of which the following is a specification, reference being had to the accompanying drawing, forming part thereof.

Fig. 1 is a plan view of the croustade; Fig. 2 is an elevation thereof; and Fig. 3 is a sectional view along the line 3—3 of Fig. 2.

I claim:

The ornamental design for a croustade, as shown.

SAMUEL E. WINDER.
